CLAIM

The ornamental design for a folding cart, as shown and described.

DESCRIPTION

FIG. 1 is a first perspective view of a folding cart showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the folding cart thereof;

FIG. 10 is an enlarged view of the selected portion in FIG. 2;

FIG. 11 is an enlarged view of the selected portion 11 in FIG. 2; and,

FIG. 12 is an enlarged view of the selected portion 12 in FIG. 2.

The broken lines shown in the drawings depict portions of the folding cart that form no part of the claimed design. The dash-dot broken lines demarcate enlarged areas and form no part of the claimed design.
